POWER CHAIN SAW ENGINE ASSEMBLY

Lloyd H. Tuggle, Shreveport, La., assignor to
Emerson Electric Company, St. Louis, Mo.

Filed Oct. 12, 1973, Ser. No. 406,035

Term of patent 14 years

Int. Cl. D8—03

U.S. Cl. D77—1 R

FIG. 1

FIG. 2

FIG. 3

FIG. 4

FIG. 5

FIG. 6

FIG. 7

FIG. 1 is a perspective view showing the rear and right hand side of a power chain saw engine assembly;

FIG. 2 is a perspective view showing the front and left hand side of the power chain saw engine assembly of FIG. 1;

FIG. 3 is an elevational view of the left hand side of the power chain saw engine assembly of FIG. 1;

FIG. 4 is an elevational view of the front of the power chain saw engine assembly of FIG. 1;

FIG. 5 is an elevational view of the right hand side of the power chain saw engine assembly of FIG. 1;

FIG. 6 is an elevational view of the rear end of the power chain saw engine assembly of FIG. 1; and

FIG. 7 is a top view of the power chain saw engine assembly of FIG. 1.

I claim:

The ornamental design for a power chain saw engine assembly, as shown and described.
